UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SHOCK-ABSORBING MECHANISM.

Application filed December 8, 1923. Serial No. 679,309.

To all whom it may concern:

Be it known that I, JOHN F. O'CONNOR, a citizen of the United States, residing at Chicago, in the county of Cook and State 5 of Illinois, have invented a certain new and useful Improvement in Shock-Absorbing Mechanisms, of which the following is a full, clear, concise, and exact description, reference being had to the accompanying 10 drawings, forming a part of this specification.

This invention relates to improvements in shock absorbing mechanisms.

One object of the invention is to provide a shock absorbing mechanism capable 15 of use wherever heavy shocks are to be cushioned, including railway draft riggings wherein a plurality of springs are provided arranged to operate in tandem.

20 More specifically, the object of the invention is to provide a mechanism of the character indicated comprising front, rear and intermediate units, each including a spring resistance element and coacting follower 25 means, wherein the units are arranged end for end longitudinally of the mechanism, with the springs disposed in tandem formation.

Other objects and advantages of the invention will more clearly appear from the 30 description and claims hereinafter following.

In the drawings forming a part of this 35 specification, Figure 1 is a horizontal, longitudinal, sectional view of a portion of a railway draft rigging showing my improvements in connection therewith. Figures 2, 3 and 4 are vertical, sectional views corresponding respectively to the lines 2-2, 40 3-3 and 4-4 of Figure 1. And Figures 5 and 6 are detailed, perspective views respectively of a central follower and an intermediate follower used in connection with my improved mechanism.

45 In said drawings, 10-10 indicate channel shaped center or draft sills of a railway car underframe, to the inner faces of which are secured front stop lugs 11-11 and rear stop lugs 12-12. A portion of 50 the drawbar is indicated at 13, to which is attached a hooded yoke 14. The shock absorbing mechanism proper is disposed within the yoke 14 and the movable parts of the draft rigging are supported by a detachable 55 saddle plate 15.

The improved shock absorbing mechanism, as shown, comprises broadly, front and rear follower casings A-A; central followers B-B; intermediate followers C-C; triple tandem arranged springs D-D-D; 60 and a retainer bolt E.

Each casing A is of generally rectangular form throughout its length and is provided with a cylindrical bore 16 adapted to accommodate the corresponding spring resistance 65 element D. At the outer end, that is, the end adjacent the corresponding stop lugs, each casing A is closed by a transverse wall 17, the opposite or inner end of the casing being open. Each casing is also provided 70 with a pair of integral extensions 18 on the opposite sides, at the outer end thereof adapted to coact with the corresponding stop lugs.

The front follower casing A is recessed on opposite sides at the inner end 75 thereof as indicated at 19-19, for a distance not less than the sum of the thickness of one of the intermediate followers C and the permissible stroke of the mechanism. The top and bottom limits of the recesses 80 19 are defined by radially extending faces 20-20 at the top and bottom of the casing, as most clearly shown in Figure 2. The rear follower casing A is similarly recessed at 85 the top and bottom thereof as indicated at 19-19, the opposite sides of the recesses being defined by similar radially extending faces 20-20, as most clearly shown in Figure 4.

The central follower members B-B are 90 of like construction, each comprising a disc

like section 21, having diametrically opposed, longitudinally extending arms 22-22 formed integral therewith. The opposite 95 longitudinal edges of each arm are cut away on planes radial to the axis of the mechanism, thereby providing longitudinally extending faces 23-23. At the free end of each arm 22 is provided a longitudinally 100 projecting central lug 24 for a purpose hereinafter described. One of the followers B has the disc end thereof abutting the inner 105 end of the front follower casing A and the arms 22 thereof extending rearwardly at opposite sides of the gear, being slidably disposed between the forwardly projecting, horizontally disposed arms 22 of the other follower B, which has the disc thereof abutting the inner ends of the rear follower casing A. The arms 22 of each follower B 110

slidably engage the curved edges of the disc 21 of the other follower B, each arm being cut away on the inner side for the entire length thereof to correspond with the curvature of the disc so as to clear the same. The curved inner surfaces of the four arms 22 define a continuous cylindrical chamber adapted to house one of the spring resistance elements D. The followers B are thus adapted for relative sliding movement with the arms of the respective followers working in the recesses 19 of the corresponding casings A, and the edge faces 22 in sliding contact with the faces 20.

15 Each of the intermediate followers C is in the form of a flat plate of generally circular form having a pair of wings 25—25 on diametrically opposite sides thereof. One of the followers C is disposed at the free ends of the arms 22 of each follower B with the wings 25 engaging the outer ends of the arms. Each of the wings 25 is centrally slotted as indicated at 26, the diametrically opposite slots 26 of each follower C being 20 adapted to accommodate the opposite lugs 24 of the corresponding follower B. The outer edges of the wings 25 of each follower C are flush with the outer surfaces of the respective arms 22 and the opposite side edges of the wings are cut away on radial lines as indicated at 27—27 so that the faces thereof will register with the faces 23 of the corresponding follower B. Each of the followers C is thus carried at the free ends of 25 the arms 22 for movement in unison with the corresponding central follower B, with the disc portion slidably disposed within the bore 16 of the corresponding follower A and the wings 25 working in the opposed recesses 30 19.

35 The spring resistance elements D are three in number, each preferably consisting of a relatively light inner coil and a relatively heavy outer coil. One of the spring resistance elements D is interposed between the two central followers B—B and one of each of the two remaining spring resistance elements D is interposed between the end wall 17 of one of the casings A and the adjacent 40 intermediate follower C.

45 The retainer bolt E has its opposite ends anchored within inwardly projecting, hollow bosses 28—28 on the end walls of the front and rear follower casings respectively, the shank of the bolt extending axially through the springs D and alined openings in the followers B and C. The retainer bolt serves to maintain the over-all length of the gear and holds the parts under initial compression. In this connection, it is pointed 50 out that the spring followers B—B and the spring followers C—C together form a complete unit which is distinct from the front and rear follower units, the same being so designed that a plurality of such units may

be used between the front and rear follower casings, without modification of the latter. It will be evident that by this arrangement, gears of various capacities may be provided, by merely varying the number of central 70 units employed.

In the specific embodiment of the invention as herein disclosed employing three springs arranged in tandem, a gear is provided which has the travel of one spring and 75 a capacity three times that of a single spring.

With the described arrangement, upon either inward or outward movement of the drawbar, one set of followers A, B and C 80 will be held stationary and the other set of followers C, B and A respectively coacting therewith will move in unison relatively toward the first named set so that the three spring resistance elements will be compressed 85 simultaneously, the central spring resistance being compressed between the two central followers B and the two end springs being each compressed between the end wall of one of the end followers A and the corresponding follower C. Compression of the springs will be limited, preventing the same from being driven solid, by the arms 22 of the respective intermediate followers engaging the inner end walls of the recesses 19 90 of the front and rear follower casings A, whereupon the forces will be transmitted directly through the two end followers A and the two central followers B to the draft 95 sills.

100 Not only is the central spring completely housed, as hereinbefore described, but it will also be noted that the end springs are also substantially completely housed, thus affording the maximum protection to the springs from deterioration by the elements. Furthermore, it will be observed that, under full load, I have provided an exceptionally strong column inasmuch as all the parts will be preferably so made as to have engagement between the various sets of shoulders simultaneously. All the parts may be manufactured at comparatively small expense, and as previously mentioned, the capacity 105 of the mechanism may be varied by simply varying the number of central units and interposing them between the end sets of parts.

110 I have herein shown and described what I now consider the preferred manner of carrying out my invention, but the same is merely illustrative and I contemplate all changes and modifications that come within the scope of the claims appended hereto.

115 I claim:

120 1. In a shock absorbing mechanism, the combination with relatively movable end followers; a plurality of intermediate followers movable in unison with each end follower, all of said intermediate followers 125

being separable from said end followers; and spring resistance means coacting with the respective followers.

2. In a shock absorbing mechanism, the combination with relatively movable end followers; of two sets of intermediate followers; means for maintaining the followers composing each set spaced a fixed distance; means separable from each set of intermediate followers for maintaining a fixed spaced relation between each end follower and the corresponding set of intermediate followers; and cushioning elements coacting with the respective followers.

3. In a shock absorbing mechanism, the combination with two series of followers, each series including spaced, end, central and intermediate followers, the followers of one set being alternated with the followers of the other set and movable relatively thereto, said intermediate and central followers being separable from the end followers; and cushioning means interposed between corresponding followers of each series.

4. In a shock absorbing mechanism, the combination with front and rear follower casings; of a pair of central followers each abutting one of said casings, said central followers each having abutment means thereon; a pair of intermediate followers

each engaging the abutment means of one of said central followers; and cushioning means interposed between the central followers, and between each follower casing and the corresponding intermediate follower.

5. In a shock absorbing mechanism, the combination with three sets of relatively movable followers; of cushioning means interposed between each set of relatively movable followers; and means for detachably connecting corresponding followers of each set.

6. In a shock absorbing mechanism, the combination of two series of followers, each series including end, central and intermediate followers, each of said followers being a separate unit; of tandem arranged cushioning means coacting with said followers.

7. In a shock absorbing mechanism, the combination with two series of followers, each series including an end follower; a central follower and an intermediate follower; of abutment means on the respective followers for maintaining the followers of each series definitely spaced; and cushioning means interposed between followers of the two series.

In witness that I claim the foregoing I have hereunto subscribed my name this 4th day of December, 1923.

JOHN F. O'CONNOR.
